I. DE KAISER ET AL.

OIL WELL HEATER

Filed Feb. 8, 1921

UNITED STATES PATENT OFFICE.

ISAAC DE KAISER, OF WILKINSBURG, AND ARTHUR G. POPCKE, OF PITTSBURGH,
PENNSYLVANIA.

OIL-WELL HEATER.

Application filed February 8, 1921. Serial No. 443,462.

To all whom it may concern:

Be it known that we, ISAAC DE KAISER and ARTHUR G. POPCKE, citizens of the United States, and residents of Wilkinsburg and Pittsburgh, respectively, in the county of Allegheny and State of Pennsylvania, have invented a new and useful Improvement in Oil-Well Heaters, of which the following is a specification.

10 Our invention relates to heating devices for subterranean wells and particularly to devices for treating crude-oil wells to increase their yield.

One object of our invention is to provide 15 a device of the above indicated character that shall effectively support combustion in a subterranean well.

Another object of our invention is to provide 20 a heater that shall constitute a self-contained heat-generating and heat-giving unit that may be lowered into a subterranean well at the end of a cable and require no other connections extending to the well mouth.

25 Another object of our invention is to provide a subterranean well heater that shall utilize continuously supplied fuel to a substantially maximum degree of efficiency.

A further object of our invention is to 30 provide a subterranean well heater that shall be simple and durable in construction, convenient to handle and economical to manufacture and maintain.

In subterranean wells, such as those containing 35 gas and other elements and, particularly, those containing crude oil, it is desirable to periodically promote the circulation of the fluid in the well. Oil wells, in particular, become clogged or sluggish by 40 the accumulation of heavy constituent fluids, such as paraffine. Under the latter conditions, the well yield falls to a very low value.

By heating a clogged well, the heavy constituents 45 may be rendered more liquid in form, which enables them to be pumped from the well and releases the lighter oils or elements that have been held back.

Heretofore, the heating of a subterranean well has usually been a very undesirable operation, because of the difficulty of access to the well and of providing economical sustained heat.

One method of heating a subterranean well is to lower bodies of iron, that have 55 been previously heated, into the well. This method is very inefficient and tedious, by reason of the small quantities of heat that may be, thus, transported and because of 60 rapid radiation.

Attempts have been made to increase the flow of oil wells by the use of nitro-glycerine but, since it is necessary to sustain a relatively high temperature for a relatively 65 long period of time, this method has not been very effective. It is, further, very expensive and dangerous.

Heating by steam has accomplished some good results but at a relatively great cost in time, labor and material, since it must 70 be accomplished by means of pipes extending to the pay sand of a well that may be several thousand feet deep.

Heat treating of subterranean wells by 75 electricity has been accomplished to a high degree of perfection, in consideration of the limitations imposed by its use. Some of these limitations are the lack of available power circuits, the inaccessibility of the wells to be treated, and the expense of providing permanent or portable power units.

In practicing our invention, we provide 80 a subterranean well heater that comprises a relatively small self-containing heat-generating and heat-giving unit that is adapted for lowering into wells and through well casings of existing types. This unit or device embodies a heated portion that gives off 85 its heat only to the well, a torch or burner for supporting a heating flame and one or more renewable fuel or gas tanks for feeding the flame.

The entire device, with pressure and control valves and other features, is hermetically-sealed against the ingress of liquid 90 thereto, from the well, and against the escape of gas and flame to the well. Further, the device is adapted to support combustion in its isolated position in a well that is void of air, may be readily handled and lowered 95 into a well, at the end of a cable or sand line, without any other connections, such as gas pipes or electrical conductors, and may be conveniently transported in standard vehicles. The device may be readily separated 100 into two or three parts so that wells of the

most isolated or difficult access may be reached. The absence of relatively long supply lines, such as electrical conductors and steam pipes, renders the device of relatively great thermal efficiency.

Figure 1 of the accompanying drawings is a diagrammatic representation of an oil well of usual character in which a heater embodying our invention is submerged.

10 Fig. 2 is a broken enlarged view, partially in elevation and partially in section, of the heater shown in Fig. 1 and

15 Fig. 3 is a further enlarged fragmentary sectional view of the heater casing as shown in Figs. 1 and 2, with a modified form of venting or heat-retarding means for the upper end thereof and a modified torch or burner chamber.

20 Referring to Fig. 1, a subterranean chamber 1, formed in a stratum 2 of oil-bearing sand, is filled with a body of crude oil 4 which it is desired to remove by means of an oil pump of usual construction (not shown).

25 Accumulations of paraffine, asphalt and other heavy hydro-carbons seriously interfere with the production of oil from the well, by clogging the interstices in the oil-bearing stratum and by filling or partly filling the perforations in the pump barrel. 30 Further, the main body of oil produced by the well may be sufficiently viscous to cause difficulty in its removal by the pump.

35 To facilitate the removal of the oil from the well, a heating device 5, constructed in accordance with our invention and to be hereinafter described, is lowered into the well at the end of a cable or sand line 6.

40 The heat from the device 5 affects the oil 4 in such manner as to permit the latter to be readily pumped from the well and, also to enhance the flow of oil into the chamber 1 from the oil bearing sands 2.

45 The heating device 5 preferably comprises sections 7 and 8 of metal tubing that are joined to each other by a union 9, and are provided with upper and lower end members 11 and 12, that may be threaded, or otherwise suitably secured, thereto, to complete a substantially totally enclosed casing.

50 A gas-escape tube 14, similarly secured to the upper end member 11, is of sufficient length to extend above the water level of a well and is provided, at its upper end, with a terminal device 15. The latter comprises 55 a nut or head member 16 that is threaded, or otherwise secured, to the tube 14 and is embraced by a hood or dome member 18. The dome-member may be held in position by an eye bolt or terminal member 19 that 60 extends into the nut 16 and is attached to the cable 6. Perforations 21, in the upper end of the tube 14, permit the escape of combusted gases to the dome member 18 that is provided with perforations 22, at its 65 lower portion, to permit the gases to escape

to the upper part of the well and to the outer air. The end members 11 and 12 of the heater 5, the union 9 and the dome 19 are tapered or rounded to avoid the end edges of the well casing or other obstructions in the well shaft to, thus, permit the free travel of the heater to and from the chamber 1.

70 The upper portion of the tubing 7, constituting the active heat-giving portion of the heater 8, is lined with a body of tube 25 75 preferably of refractory heat-intensifying material, such as fire clay or other suitable material, and contains a body 26 of similar material that is supported by a perforated refractory, or other incombustible, partition 27. The partition 27 may be a separate member of similar material or constitute an integral portion of a heat insulating tube 28 that serves, similarly to the tube 25, to protect a portion of the tube 7 and surrounds a 80 region in the latter that functions as a combustion chamber 29. As shown in Fig. 2, a cylindrical heat-insulating block 30 is disposed below the combustion chamber 29 and is supported on an inwardly projecting 85 transverse annular flange 31 on the union 9.

90 A torch or burner 32, similar to that employed in usual and well known welding outfits and comprising a head 33, a mixer 34 and stop cocks or valves 35 and 36, extends 95 through an opening 37 in the block 30, so that a flame 38 may impinge against the partition 27 and ascend through a portion of the heat-intensifying material 26. The burner 32 is supported by the upper of a 100 pair of gas tanks or cylinders 39 and 40 that are arranged in base-to-base relation in the section of tubing 8, with a felt, or other yieldable shock-absorbing, pad 41 therebetween. The tanks 39 and 40 are supported 105 on a saddle supporting member 42 disposed at the lower end of the tubing 8. The tank 39 is connected to the burner 32 through a pressure regulating device 43 and the valve 36. The tank 40 is connected to the burner 110 44 through a similar pressure regulating device 44, a pipe 45 and the valve 35. The tanks 39 and 40 are, preferably, of slightly less 115 diameter than the interior diameter of the tube 8 to admit the pipe 45 that may be of cylindrical or flat tubing, formed to permit the tanks to be of maximum diameter. The arrangement of parts is such that, by unscrewing the section of tubing 8 from the union 9, the burner 32 and the tanks 39 and 120 40 may readily be removed for inspection and replacement. One of the tanks 39 and 40 may contain oxygen or compressed air and the other acetylene, calorene, gasol, blau 125 gas, carbo-hydrogen or any other combustible fluid.

130 For facility in handling and shipping, the device may be separated into several easily-assembled units. One such unit may comprise the tube 14 and the terminal device 130

15, attached to each other but separated from the remainder of the heater. Another unit may comprise the upper tube 7 of the heater 5, the union 9, the top member 11 and 5 the other contents of the tube 7, excepting the burner 32. A still further unit, or collection of units, may comprise the lower tube 8, the saddle 42 and the lower end member 12, either with the burner 32 and the tanks 10 39 and 40 in the tube 8 or separate therefrom.

In operation, assuming the parts to have been transported to a well, the first operation is, preferably, to attach the tube 14 to 15 the upper end member 11. Fresh tanks 39 and 40 of oxygen and acetylene, or of other elements above mentioned, may be secured in operative relation to the burner and to its accessory valves and pressure regulators.

20 At a location sufficiently removed from the well mouth to avoid igniting gases from the well, the flame 32 may be started, and adjusted by means of the valves 35 and 36 and the pressure regulators 43 and 44. The 25 tanks are then placed in the tube 8, the burner inserted through the opening 37, in the block 30, and the tubes 7 and 8 secured together, by means of the union 9. The device may then be raised, by the cable 6 that extends 30 over a pulley wheel at the top of the well derrick, and quickly lowered into the well.

An obvious alternative arrangement of parts, which would require only slightly different manipulation, is to have the pipe 45, 35 leading from the lower tank 40 to the burner 32, permanently mounted in the tube 8, as by spot welding at its ends or by other suitable means. This construction renders it necessary to remove the lower end member 40 12 to adjust the pressure regulator 44 and to connect the latter to the pipe 45 but has the advantage of permitting the tanks 39 and 40 to be placed in the tube 8 before igniting the burner 32.

45 Crude oil wells are usually provided with a pocket or chamber 46 for seating an anchor to steady the pump and it is in this pocket that the lower unheated portion of the heater 5 is placed. In the few wells that 50 may not have such a pocket, it is a comparatively simple operation to lower a drill and to drill the few feet necessary to properly position the heater. This arrangement permits the upper and active heating portion 55 of the heater 5 to be positioned in the chamber 1 at the oil bearing stratum.

At the upper end of the tube 7, a heat-insulating member 47, having a tapered opening 48, is positioned in the member 11 to 60 protect the latter and to direct the gases of combustion toward the tube 14. As shown in Fig. 2, a copper mesh screen 49 may be provided, between the member 47 and the refractory material 26, to prevent the passage of flame into the tube 14.

As shown in Fig. 3, in place of the screen 49, a series of baffle plates 59, having offset openings 51 and refractory spacing rings 52, may be provided to cool the gases, before they enter the tube 14.

Primarily, our invention consists in the provision of a self-contained, heat-giving and heat-generating unit of simple construction, ready transportation and manipulation and of effective operation, that does not injure the well or casing and requires no source of energy above ground. In this aspect, our invention, therefore, contemplates all similar self-contained units, such as may be constructed to employ storage batteries, reactive gases, liquids and solids and, also, comprehends obvious changes, such as the elimination of one of the tanks, and providing the other with oxygen or compressed air for burning a combustible material, such as charcoal. In the latter case, no material change in the construction of our device, as shown, is necessary. The charcoal may be substituted in the place of the material 26 and a single oxygen or compressed air tank placed in the tube 8 and connected to the burner 32, through one of the valves 35 and 36 or to a similar burner having only one such valve.

In the form of our invention, in which 95 charcoal or other combustible ash-forming material is used, the block 30 may be omitted and the construction shown at an intermediate portion of Fig. 3 employed. In this construction, the burner 32 is protected by 100 a heat-insulating tube 53 having a tapered upper end 54 to deflect ashes that may sift through the partition 27, adjacent to the burner into an ash-receiving chamber 55, the space included by which is partially occupied 105 by the block 30, in the form of our invention shown in Fig. 2. The tube 53 may constitute a portion of a discoidal member 56 that is supported on the flange 31 of the union 9. Also, in this form, the tube 28 may 110 be constructed longer, to constitute a lining for the chambers 29 and 55.

While we have shown and described particular forms of our invention, changes may be effected therein, without departing from 115 the spirit and scope thereof, as set forth in the appended claims.

We claim as our invention:

1. A subterranean well heater unit for disposition in a well, comprising a heat-conducting element for heating the well by heat radiation therefrom only and means to be disposed entirely in the well for heating said element and generating a continuously renewed supply of said heat for a predetermined period of time.

2. A subterranean well-heating device comprising an enclosed vessel having means for disposing of combustion gases generated therein, and means for supplying and sup-

120 125 130

- porting combustion entirely within the vessel, the heat of said combustion being primarily for conduction to the well through closed walls of said container.
5. A subterranean well heater unit for disposition in a well, comprising a container embodying closed walls through which substantially all of the heat of the heater is transmitted to the well, heating means for effecting said heat disposed in said container and supply means for said heating means to be entirely disposed in the well.
10. A subterranean well heater unit for disposition in a well, comprising a container embodying closed walls through which substantially all of the heat of the heater is transmitted to the well and means to be entirely disposed in the well for causing said heat in said container and generating a continuously renewed supply of said heat for a predetermined period of time.
15. A subterranean well heater unit for disposition in a well comprising a container embodying closed walls through which substantially all of the heat of the heater is transmitted to the well, a gas burner in the container for initiating said heat, and a source of gas supply for said burner to be entirely disposed in the well.
20. A heating device comprising an enclosed vessel having outlet means for combustion gases only and constituting the only exception to total enclosure, and means for supplying and supporting combustion entirely within the vessel.
25. A subterranean well heater comprising a container, gas-escape means therefor, a body of material to be heated in the container, the heat from said material to be transmitted to the well through closed walls of the container, a torch or burner for heating said material, and a gas-storage chamber connected to said burner.
30. A subterranean well heating device comprising a tubular container, gas-escape means therefor, a body of material to be heated in the container, the heat from said
- material to be transmitted to the well through closed walls of the container, a torch or burner for heating said material, and a renewable gas-storage tank connected to the burner.
35. A subterranean well heating device comprising a tubular container, gas-escape means therefor, a body of heat-intensifying material disposed in the container, a torch or burner for heating said material, and a plurality of replaceable tanks containing interactive flame-producing elements for the burner, said tanks constituting a portion of the device for lowering into a well.
40. A subterranean well heating device comprising a container for heating the well through its closed walls, gas-escape means therefor, a torch or burner supporting a flame in the container, and a gas-storage chamber therein connected to said burner.
45. A subterranean well heater comprising a container, gas-escape means therefor, a body of heat-giving material disposed in the container, a burner for projecting a flame against said material, a plurality of fluid-containing tanks removably disposed in said container, the fluid of said tanks cooperating to form flame at said burner, and means for connecting and for controlling the pressure and flow of said fluids to said burner.
50. A subterranean well heater comprising a container, gas-escape means therefor, a protective lining for a portion of the container, a body of refractory material disposed in the container, a gas-burner for heating said refractory material, a plurality of gas tanks removably disposed in the container, and means for connecting and for controlling the pressure and flow of gases from said tanks to said burner.
55. In testimony whereof, we have hereunto subscribed our names this 7th day of February, 1921.
- ISAAC DE KAISER.
ARTHUR G. POPCKE.
